G. STOBWASSER.

Lamp.

No. 58,361.

Patented Sept. 25, 1866.

UNITED STATES PATENT OFFICE.

GUSTAR STOBWASSER, OF BERLIN, PRUSSIA, ASSIGNOR TO E. DOUGLAS, SON & CO., OF NEW YORK CITY.

IMPROVEMENT IN LAMPS.

Specification forming part of Letters Patent No. 58,361, dated September 25, 1866.

To all whom it may concern:

Be it known that I, GUSTAR STOBWASSER, of Berlin, Kingdom of Prussia, have invented an Improved Lamp; and I do hereby declare that the following is a full, clear, and exact description thereof, which will enable others skilled in the art to make and use the same, reference being had to the accompanying drawings, forming part of this specification, in which—

Figure 1 is an elevation of a lamp provided with my improvement; Fig. 2, an enlarged exterior view of the lower part of the fountain of the same; Fig. 3, an enlarged vertical section of the lower part of the fountain and the socket in which it is fitted. $x x$, Fig. 4, indicate the line of section. Fig. 4 is a horizontal section of Fig. 3, taken in the line $y y$; Fig. 5, also a horizontal section of the same, taken in the same line, $y y$, as Fig. 4, but showing a different portion of the fountain; Fig. 6, a detached perspective view of the socket in which the lower part of the fountain is fitted.

Similar letters of reference indicate like parts.

This invention relates to a new and improved lamp of that class which are provided with elevated fountains—that is, lamps which have their fountains above the level of the burner, so that the same may, by static pressure, be provided with oil until the fountain is exhausted or its contents entirely consumed.

The difficulty hitherto attending this class of lamps has been the liability of the burner being unduly supplied with the oil or burning material, and the danger of explosions if a volatile oil be used—such, for instance, as the higher grades of coal-oils—and also the danger of the spilling of oil and the escape of the same from the fountain in adjusting the latter to and detaching it from the lamp—difficulties which it is believed are fully obviated by my invention.

A represents the base, and B an upright rod attached centrally thereto. C is a slide fitted on the rod B, and secured at any desired height thereon by a set-screw, a. D is a tube which communicates with the slide C and projects from opposite sides of the slide C, one arm, a' , of said tube being curved and having the ordinary Argand burner E attached to its end, the other arm, a'' , communicating with a vertical socket, F, within which there is fitted and permanently secured a cylinder, G, having a vertical groove or recess, b, extending its whole height, and a horizontal groove, c, which communicates with the vertical groove b, the groove c extending around about one-quarter of the circumference of G. (See Figs. 4, 5, and 6.) This cylinder G has a hole, d, made in it in line with the orifice of the arm a'' of tube D.

H represents the fountain, which contains the oil or other fluid or material to be burned. This fountain may be of any desired form or shape at its upper part, above the socket F; but its lower part, e, is of cylindrical form, and has a cylinder, f, fitted upon it so as to turn freely. The cylinder f also has a rib, a^x , attached vertically to it to pass into the groove or recess b in cylinder G, and said rib has a notch, b' , made in it to receive the pin i of the cylindrical part e of the fountain, said pin passing through a horizontal slot, c^x , in f. The lower end of the part e of the fountain has a screw-plug, I, fitted in it, and said part e has a hole, g, made in it, and the cylinder f has a corresponding tube, h, made in it, as shown in Figs. 3, 4, and 5.

The lower cylindrical part, e, of the fountain has a pin, i, projecting from it, said pin being of such a size as to fit into the groove or recess b of the cylinder G, and also to pass into the horizontal groove c.

The fountain H is filled with oil when detached from the lamp, the screw-plug I being removed for that purpose, or the cylinder f turned on the part e until the holes g h are brought in line with each other, the fountain being inverted while being filled. When the fountain is filled the cylinder f is turned back on e until the notch b^x in the rib a^x covers the pin i of e, and the lower part of the fountain may then be fitted in the socket F, the rib a^x on f passing down in the groove or recess b in cylinder G, which cannot be done unless the pin i is within the notch b^x of the rib, as the top of cylinder G would prevent it, and when the cylinder f is turned on e to cause the notch b^x to cover the pin i the holes g h are out of line with each other, and, consequently,

no oil can escape from the fountain while the lower part of the latter is being adjusted in the socket. (See Fig. 5.)

After the lower part of the fountain is adjusted in the socket F, the fountain H is turned from left to right, as indicated by arrow 1, Fig. 5, and the pin i moves in the horizontal groove c, the holes g h being thereby made to register more or less fully or perfectly with each other, according to the quantity of oil required to be fed to the burner; and in order to withdraw the fountain H from the burner the fountain requires to be turned in the contrary direction, as indicated by arrow 2, Fig. 4, in order that the pin i may enter the notch b^x of the rib a^x. Without this the fountain could not be removed, and in thus turning the fountain the holes g h are thrown out of line with each other, and the escape of oil from the fountain avoided. By this turning of the fountain the flame may be extinguished at any time, as the supply of oil to the burner is thereby cut off, and the height of the flame may also be regulated by increasing or diminishing the supply of oil to the burner.

The arrangement is extremely simple, and is not liable to get out of repair. The supply of oil to the burner may be regulated, as re-

quired, with the greatest facility, so that there need be no danger of an overflow from the burner, and no danger of oil escaping from the fountain, either in adjusting the fountain to the lamp or removing it therefrom.

I do not claim the Argand burner, for that is an old and well-known device; but

I do claim as new and desire to secure by Letters Patent—

The pin i, attached to the lower cylindrical part, e, of the fountain, and having a cylinder, f, fitted loosely on e, and provided with a vertical rib, a^x, having a notch, b^x, made in it, and a horizontal slot, c^x, in combination with the vertical groove or recess b and the horizontal groove c in the cylinder G, which is secured in the socket F, the cylindrical part e of the fountain and the cylinder f having holes g h made in them, and all arranged to operate substantially in the manner as and for the purpose set forth.

The above specification of my invention signed by me.

GUSTAR STOBWASSER.
